UNITED STATES PATENT OFFICE.

ROBERT ANDERSON, OF CINCINNATI, OHIO.

FORM WORK FOR CONCRETE CONSTRUCTION.

1,014,738.

Specification of Letters Patent.

Patented Jan. 16, 1912.

Application filed December 27, 1910. Serial No. 599,594.

To all whom it may concern:

Be it known that I, ROBERT ANDERSON, a citizen of the United States of America, and resident of Cincinnati, county of Hamilton, and State of Ohio, have invented certain new and useful Improvements in Form Work for Concrete Construction, of which the following is a specification.

This invention relates to molds or forms 10 employed in concrete construction.

The forms employed in concrete construction are assembled into a structure, which may be termed "the form work" and this structure or form work must be sufficiently 15 strong and rigid to support the concrete and the reinforcing members for the concrete, prior to the time that the concrete is capable of supporting itself, or, in other words, prior to the time that the concrete 20 sets to form a monolithic structure. The usual means employed in building the forms and in assembling them to form the form work, prevents the form work from being wrecked, or dismantled, without damaging 25 the individual forms of which it is composed and leaving them in a condition unfit for use again. All prior form work known to me is so badly damaged during the process of erecting or dismantling it, 30 that much of the lumber is left in a condition, which prevents its further use for form work, and that the individual forms must be practically rebuilt before they can be employed again.

An object of my invention is to produce a form work consisting of separate forms or molds, assembled prior to erection and provided with means which readily co-act with other forms, to make an ordinary temporary 35 structure for receiving and supporting the reinforcing members and the concrete, and in which said co-acting means may be readily disengaged to dismantle the temporary structure, without in any way damaging or 40 detrimentally affecting the separate molds or forms, so that these forms may be reassembled without reconstructing the individual molds or forms, to form the temporary structure for another building. These and 45 other objects I attain by means of form work embodying the features herein de-

scribed, and illustrated in the drawings accompanying this application and forming a part thereof.

In the drawings:—Figure 1 is a perspective view of form work embodying my invention, and shows the arrangement of the column, girder, beam, column cap and floor panel forms. The view is taken from below the girder, beam and floor panel forms. Fig. 55 2 is a perspective view of the form work illustrated in Fig. 1, and is taken above the girder, beam and floor panel forms. Fig. 3 is a plan view of a column cap form, in connection with fragmental views of girder and beam forms, and illustrates a form of connection between the column, girder and beam forms, which may be employed with my invention. Fig. 4 is a perspective view of the 60 top portion of a column form, in connection with fragmental views of a girder and a beam form, and illustrates the manner in which the ends of the girder and beam forms are supported in the organized form work 65 illustrated as an embodiment of my invention. Fig. 5 is a fragmental perspective view and illustrates a connection between beam and girder forms, which may be employed with the illustrated embodiment of my invention. Fig. 6 is a plan view of girders, 70 beams, and their connections.

In the form work illustrated as an embodiment of my invention, I have employed disintegrable column forms 6, which are formed of separate panels, capable of being 85 temporarily secured together for the purpose of forming a column mold, and also capable of being taken apart and removed from the column, after it is formed. Any column form of this general description may 90 be employed in connection with my invention. Each column form illustrated, is provided with a supporting shelf 7, which is located at the upper end of the form, flush with the tops of the form boards or panels, 95 and which is adapted to support a column cap form 8, and the ends of girder and beam forms 9 and 10. The shelf 7 of each of the column forms 6 illustrated, is employed with other devices in securing the 100 separate panels comprising the column form in place, but such a construction is not es-

sential to the purposes of my invention. In erecting the form work, I preferably, but not necessarily, form concrete centering lugs 19 on the foundation of the concrete structure, which are of the shape of the concrete columns and eventually form a portion of the concrete columns of the structure. I then assemble the column forms around these centering lugs and support each column form on elevating or height adjusting wedges 11, which are located adjacent to the centering lugs and under the lower edges of the column forms. The column forms can be brought to plumb and raised to the desired position by shifting the positions of the wedges, relative to the supported edges of the column forms. The girder forms 9 are located in place on the column forms by supporting their ends on the shelves 7 of adjacent columns. I have adopted the term "girder" for a beam which supports the ends of transversely extending beams, and for convenience of description, I will term the form for such beams "girder forms." The ends of the beam forms 10, which extend between adjacent column forms are also located on the shelves 7. After the girder and beam forms 9 and 10 are in place on the column forms, the column caps 8 are located on the shelves 7, and the beam forms 12, located between adjacent girder forms, are mounted on the girder forms, and the joists of the floor panel molds are then mounted on the beam and girder forms to support the panels. After the form work is erected, the reinforcing members for the concrete structure are located within and upon it and the forms are then filled with concrete. The individual members or forms comprised in the form work are all so constructed, that the form work can be dismantled and removed from the concrete structure, without in any way damaging the forms. In the operation of dismantling the form work, the first step is the removal of the column forms from the completed concrete columns. This is accomplished by removing the supporting or adjusting wedges 11 and releasing the panels which form the molds, so that the panels can be separately removed from the column. With the construction illustrated, there is nothing to prevent the removal of the column forms after the wedges 11 are removed, since the girder, beam and cap forms merely rest on the shelves 7 of the column forms. Shelves 7 therefore are independent of the girder and cap forms, so that when the column form is lowered, the shelves separate from the girder beam and cap forms. It will be apparent to those skilled in the art that auxiliary shores may be employed for the purpose of supporting and holding the girder,

beam and floor panel forms in place. These 65 shores have been omitted from the drawings for the sake of clearness.

After the column forms are removed, the next step is the removal of the beam forms 10 and 12. These forms are so arranged 70 that they may be dropped down away from the concrete beams which they inclose. I accomplish this by providing inclined ends 75 on each beam form, so that the forms are longer at the bottom than at the top, and by providing correspondingly inclined battens 80 on the adjacent forms, against which the inclined ends of the beam forms abut. For example, the beam forms 10 are provided with inclined ends, and with inclined 85 battens 13 (Fig. 4), which are adapted to abut against and to be secured to inclined battens 14 of the column cap forms 8 (Figs. 1, 2 and 3). The battens 13 are secured to the battens 14 by means of double-headed 90 nails 15, which hold them firmly in place and yet form a temporary connection, which may be disconnected without damaging the battens. Each double-headed nail is provided with a head which projects from the 95 surface of the timber, when the nail is driven home, so that it is easily accessible for the purpose of withdrawing the nail. After the column forms 6 are removed and the double-headed nails 15 are withdrawn from the battens 14, and the supporting shores for the beam forms 10 are removed, there is nothing to hold the beam forms in place, or to prevent them from slipping downwardly away from the completed concrete beam. With 100 the inclined end construction of the beam forms, the forms are incapable of being jammed in place, so that they cannot be easily removed. The slightest downward movement of the beam forms will free the 105 battens 13 from the battens 14 and absolutely release the beam.

The beam forms 12 are similar in construction to the beam forms 10, and their ends are supported on removable blocks 16, 110 secured to the girder forms 9 by means of double-headed nails. The girder forms 9 are each provided with openings 17, which are located at the points of connection between the girder and beam forms, and the 115 removable blocks 16 are so located on the girder forms, that the ends of the beam forms will register with the openings 17, when the beam forms are in place on them. At one end of the beam, the connection employed between girder and beam forms, consists of vertical battens 18, with inclined faces, on each side of the openings 17. The inclined faces of the battens 18 correspond in inclination to the ends of the beam forms 12, 120 and the battens 13 of the beam form abut against the inclined faces and are secured to the battens 18 by means of removable or 125

double-headed nails. This form of connection cannot be conveniently employed at the other end of the beam forms 12, for the reason that it would be difficult to swing the 5 beams to place on the blocks 16 in assembling the form work. In addition to this, the girder form 9 could not be removed from the finished concrete structure without being damaged, if the girder form supported more 10 than one set of parallel beam forms. This, however, will be described more fully hereinafter, in connection with the description of the method of removing the girder forms. For the reasons stated, I provide a special 15 form of connection between one end of each beam form 12 and the girder form, which consists in replacing one of the battens 18 by a key 20 and a supporting batten 21. The key 20 is provided with an inclined face 22, which corresponds in inclination to the 20 inclination of the ends of the beam forms, and an inclined face 23, which is located against a correspondingly inclined face of the batten 21. The batten 21 is permanently 25 secured to the girder form, but the key 20 is adapted to be located in place, after the beam form 12 is mounted on its supporting block 16. The key is of such shape, that it 30 will coöperate with the beam and girder forms to complete the connection between them and in effect to form a portion of the beam form. In addition to this, the face 23 of the key 20 is so inclined that the key is narrower at its inner than its outer edge 35 and forms a wedge, which is located between the batten 21 and the finished concrete beam, and which may be easily removed in the operation of dismantling the form work, as will hereinafter be described. The key 20 40 may be secured temporarily to the batten 21 by means of double-headed or removable nails.

In girder forms where there are more than one beam opening, alternate openings 45 in the girder form are made wider for the reception of keys 20, and are arranged so that each beam shall have a key at one of its ends, as illustrated in Fig. 6. The purpose of this is two-fold; first, it provides that the 50 girder form between two molded beams shall be of less length than the distance between the adjacent faces of the beams, so that the girder form may readily be lowered away from the molded beam, and, second, it enables an operator to rest a beam form upon 55 one girder form and to swing it into place, past the key opening, in the other girder form, so as to rest upon the supporting block 16 of the other girder form, after 60 which the beam form may be easily pushed to place and the key 20 be inserted to lock it there, as is illustrated in Fig. 6.

The beam forms 12 are removed from the finished beams by withdrawing the double-

headed nails and thereby removing the 65 blocks 16. The same conditions exist with reference to these beam forms as has been described in connection with the beam forms 10, and there is no possibility of the ends of the beam forms binding or becoming 70 jammed, so that the forms cannot be removed.

Removable joists 24 are mounted on the beams 10 and 12, for the purpose of supporting floor panel forms 25, which form a 75 part of the form work. The floor panels are supported at their edges by the column caps, beams and girders, so that they are not removed with the beam forms 10 and 12 and the joists 24. 80

The girder forms 9, as has been stated, are supported at their ends on the shelves 7 of the column forms, and, in the illustrated embodiment of my invention, I have found it convenient to provide straight or vertical 85 ends for these molds. As illustrated, each end is provided with vertical battens 26, which are adapted to abut against and engage vertical battens 27, provided on the column caps 8. If desired, the battens 26 and 90 27 may be secured together by means of removable or double-headed nails, as before described. When the girder forms 9 are designed to support more than one set of beam forms, as illustrated in Figs. 1 and 2, it is 95 necessary to provide means for releasing the form, so that it may be taken down intact, from the concrete structure. It is impossible to remove a form without damaging it where the wood of the form is located between and is in contact with concrete members of the finished structure. For this reason the keys 20 are provided, so that the separate parts of the girder form 9, located between parallel concrete beams, may be easily removed, without in any way damaging 100 the girder form. In addition to this, each column cap 8 is beveled at 28, as shown in Fig. 3, so that it forms in effect a wedge, which is located between the vertical end of 110 the girder form and the concrete column cap. The keys 20 are so located in the form work, that each portion of a girder form located between two parallel beams, will be provided with one set of keys. 115

After the beam forms 12 have been removed from the girder forms, the next step is to remove the column cap forms 8, the girder forms and the floor panel forms 25. This is accomplished by removing the keys 120 20 from between the concrete beams and the battens 21 of the girder forms, and by also removing the column cap forms and in this manner freeing the girder forms. It will be remembered that the column cap forms were 125 supported by the shelves 7 of the column forms only and that therefore they may be removed from around the finished column

caps by simply removing the double-headed nails, which secure them to the battens 27, and then withdrawing them laterally, so that their beveled edges 28 are removed 5 from between the ends of the girder forms and the concrete column caps. This operation, together with the operation of removing the keys, may be easily performed, since the wedge-shape of both the keys and the 10 beveled portions of the column caps prevents them from binding or becoming tightly wedged in place between the form work and the finished structure. After the form work is dismantled and removed, the blocks 15 16 may be again secured to the girder forms and the form work may be again assembled, as has been described, for the purpose of constructing another portion of the concrete structure, or for the purpose of constructing 20 another concrete structure.

What I claim is:—

1. A form-work for molding concrete buildings, consisting of a column form with an independent shelf flush with its upper 25 edge, beam forms resting upon the shelf, and removable cap forms joining the ends of the beam forms and constituting a part of the molding device, whereby when the column form is removed, the shelf is lowered 30 therewith from beneath the beam and cap forms.

2. A concrete building form-work consisting of column forms, girder and beam forms, the column forms having independent 35 shelves at their upper ends, the girder forms and beam forms resting upon the shelves, and removable cap forms between the ends of the girder and beam forms resting upon the shelves and filling the space between the 40 girder and beam forms.

3. A concrete building form-work consisting of column forms, girders, beam and column cap forms, the column forms having independent shelves at their upper ends, the 45 girder, beam and column cap forms resting upon the shelves, the cap forms filling in the space between the girder and beam forms and securing them temporarily together.

4. A concrete building form-work consisting of column forms, girder and beam forms resting upon the column forms, removable 50 connections which secure the girder and the beam forms upon the top of the column forms, and means resting on the floor for engaging the sides of and supporting the column forms temporarily above their supporting floor.

5. In a form work for concrete structures, disintegrable column forms, removable 55 wedges for supporting said forms, column cap forms supported on said column forms, girder and beam forms supported on said column forms and located between column

cap forms, beam forms supported between the girder forms, and downwardly detachable connections between said column cap and girder forms and said beam forms. 65

6. In a form work for concrete structures, separately formed disintegrable column forms, removable wedges for supporting said 70 forms, form supporting shelves on said column forms, beam and cap forms located upon the shelves and comprising beam forms provided with inclined ends supported by said shelves, and column cap forms located on 75 said shelves and provided with inclined members coöperating with the inclined ends of said beam forms.

7. In a form work for concrete structures, separately formed disintegrable column 80 forms, a form supporting shelf mounted on each column form, beam and cap forms located upon the shelves and comprising beam forms provided with inclined ends supported on said shelves, column cap forms supported 85 on said shelves and provided with inclined members coöperating with the inclined ends of said beam forms, and girder forms supported on said shelves.

8. In a form work for concrete structures, a separately formed disintegrable column form, a shelf mounted on said column form, girder forms supported by said shelf, beam forms provided with inclined ends supported by said shelf, and a column cap form located 90 on said shelf coöperating with said girder forms and provided with inclined members which coöperate with the inclined ends of said beam forms. 95

9. In a form work for concrete structures, a separately formed disintegrable column form, removable wedges supporting said form, a shelf located on said form, beam forms provided with inclined ends supported by said shelf, girder forms supported by said 100 shelf, a column cap form located on said shelf and coöperating with said girder forms and provided with inclined members, which coöperate with the inclined ends of said beam forms, beam forms located between 105 said girder forms, and blocks removably mounted on said girder forms for holding said last mentioned beam forms in place. 110

10. In a form work for concrete structures, a girder form, a beam form provided with inclined ends, a removable block mounted on said girder form for supporting one end of said beam form, and a double-tapered removable key between one end of said beam and said girder form. 115

11. In a form work for concrete structures, girder forms, beam forms located between adjacent girder forms and provided with inclined ends, removable blocks mounted on the girder forms for supporting 120 the ends of the beam forms, and battens 125

provided with inclined faces mounted on the girder forms for coöperating with the inclined ends of said beam forms.

12. In a form work for concrete structures, girder forms, beam forms located between said girder forms and provided with inclined ends, removable blocks mounted on the girder forms for supporting the ends of the beam forms, battens provided with in-

clined faces permanently mounted on said girder forms and coöperating with the inclined ends of said beam forms, and double-tapered removable keys located between one end of each beam form and a girder form.
